UNITED STATES PATENT OFFICE.

FRANCIS M. EVERINGHAM, OF SYRACUSE, NEW YORK, ASSIGNOR OF ONE-FOURTH TO NELSON H. STRONG, OF SAME PLACE.

ROAD-SCRAPER.

SPECIFICATION forming part of Letters Patent No. 360,380, dated March 29, 1887.

Application filed October 11, 1886. Serial No. 215,834. (No model.)

To all whom it may concern:

Be it known that I, FRANCIS M. EVERINGHAM, of Syracuse, in the county of Onondaga, in the State of New York, have invented new and useful Improvements in Road-Scrapers, of which the following, taken in connection with the accompanying drawings, is a full, clear, and exact description.

This invention relates to the class of road-scrapers designed chiefly for building and repairing roads and which have the mold-board or scraping-bar carried under a frame mounted on carrying-wheels.

The invention consists in an improved construction and combination of the constituent parts of a road-scraper which possesses superior efficiency of operation and many advantages over other machines of its class, all as hereinafter more fully described, and specifically set forth in the claims.

In the annexed drawings, Figure 1 is a side elevation of my improved road-scraper. Fig. 2 is a vertical longitudinal section of the same. Fig. 3 is a top plan view, Fig. 4 a rear end view. Figs. 5 and 6 are enlarged vertical sections taken on line $x-x$, Fig. 3, showing the mold-board respectively in its operative position and in its dumped position. Fig. 7 is an enlarged detail side view of the combined hinged and swiveled connection of the mold-board to its support, and Fig. 8 is a rear view of that part of the aforesaid connection which is attached directly to the mold-board.

Similar letters of reference indicate corresponding parts.

The carriage of the road-scraper consists, chiefly, of the front and rear axles, A A', wheels W on said axles, the head-block A'', pivoted on the forward axle by the king-bolt in the usual manner, and longitudinal stringers S S, secured at opposite ends to the head-block A'' and rear axle, A'. Said stringers are tied together intermediate the two axles by cross-beams F F, firmly secured to the stringers, and central between said stringers is a longitudinal beam, E, secured to the cross-beams F F. A driver's seat, G, is mounted on the forward portion of the carriage, and a platform, H, is suspended from the rear portion of the carriage for carrying the operator of the machine.

Across the top of the described carriage are placed two beams, C C', pivoted at their centers to the carriage at points at the center of the line of draft. Said beams are thus allowed to swing horizontally into different angles to the line of draft. They are made to move in unison, and are maintained parallel with each other by longitudinal bars D D, of equal length, pivoted to the ends of said swinging beams. By means of a suitable clamp or clamps the swinging beams C C' are retained in their desired position. These clamps are represented in the form of longitudinal bars e e, pivoted to posts e' e', secured to the forward ends of the stringers. Said bars lie across the top of the swinging beam C', and are provided with notches e" e" at different points of the lengths of the bars, which notches are adapted to engage ribs or bars d d, secured to the top of the swinging beam.

To the rear or free end of each bar e is connected a rod or strap, e, which is extended vertically through the sill S, and has its lower end connected to a lever, e', pivoted to the under side of the sill. The free end of said lever is extended rearward, so as to be easily accessible by the operator standing on the platform H. By raising the free end of the lever e' the bar e is lifted to liberate the swinging beam when desired to shift the same into a different angle to the line of draft, and by depressing the said lever the bar e is drawn down onto the swinging beam. The rib d on said beam, entering one of the notches e" of the bar e, serves to retain the swinging beam in its position. To the carriage is rigidly secured a downward-projecting ratchet, f, which the lever e' engages, and is thereby retained in its depressed position.

To each end of the swinging beam C is connected a hanger, g, and on the two hangers are hinged, by their forward ends, two arms, B B, which are arranged at opposite sides of the machine and carry by their rear ends the mold-board or scraper proper, M. The hinged connections of the forward ends of the arms B B allow the rear ends of said arms to be raised and lowered, and their movements are in arcs, the chords of which arcs are more or less rearwardly inclined, and consequently in raising the rear ends of the aforesaid arms the mold-

board or scraper M is carried to a greater or less degree rearward, and thus enabled to easily free itself from the substances which have been gathered on the front thereof. I render 5 the aforesaid movement of the arms B B adjustable, to vary the inclination of the arcs in which they move, by providing the hangers g g each with two or more holes at different points in the length thereof, and to the forward ends of the arms B B, I attach straps, each of which is provided with an eye for the reception of the pin or bolt by which the strap is hinged in one of the holes in the hanger g. By shifting the pin or bolt from one to another of the holes in the hanger g the forward end of the arm B is raised or lowered, and the angle of inclination of the arc in which the rear end of the arm moves is varied accordingly.

20 The attachment of the mold-board M to the arms B B, I make as follows: To the rear end of each of said arms I attach a rigid pendent bracket, a, on which I swivel longitudinally one of the leaves of a hinge, b, arranged with its joint horizontally and at or near the lower extremity of the bracket a. The axis of the swivel is at right angles to the joint of the hinge and inclined slightly rearward at its upper end. The other leaf of the hinge is pivoted axially at right angles to its place on a plate, h', attached to the back of the mold-board. The described combined, swiveled, hinged, and pivoted connection forms a universal joint, which allows the mold-board to stand at different angles to the line of draft and to be dumped with its top forward when desired, as illustrated in Fig. 7 of the drawings. The shifting of the mold-board in its position in relation to the line of draft causes 35 the change of the position of the hinge on the mold-board, as represented in Fig. 8 of the drawings.

The rear ends of the arms B B are supported 40 adjustably vertically by means of cranked shafts or rods i i, mounted in boxes j j on the swinging beam C, and having the cranks i' on their outer ends connected with the rear or free ends of the beams B B by hangers or rods h h. The connection of the said rods with 45 cranks i' is made adjustable by providing each of said parts with a series of holes at different points in the length thereof for the reception of the coupling-bolt. To the inner cranks, i'', which constitute the manipulating levers, I 50 connect suitable pawls, l l, adapted to engage toothed sectors m m, secured to the beam C. By manipulating the said inner cranks, i'', and their pawls l l, the operator, standing on the platform H, is enabled to raise and lower the 55 rear ends of the arms B B and lock them in the requisite position to cause the mold-board to scrape the road to the desired depth, and also unlock said arms and raise them with the mold-board when desired to dump the latter, 60 as hereinafter described.

65 The means for dumping the mold-board and for restoring it to its operative position con-

sists of a guide-post, n, for which I prefer to employ the rod by which the forward end of the platform H is suspended from the carriage, 70 and which also serves to pivotally connect the swinging beam C to the carriage. A hinge, p, is arranged with its joint horizontally near the bottom of the mold-board, and has one leaf pivoted on the back of the mold-board and 75 braced by a strip, q, placed across said leaf and fastened at its ends to the mold-board. The other leaf of the hinge is provided with an eye, by which it is connected to the guide-post n and adapted to slide vertically thereon. 80 To the upper end of the leaf, which is pivoted on the mold-board and projects above the same, is connected a latch, o, the free end of which is extended rearward, so as to be easily accessible by the operator standing on the platform 85 H. Said latch is provided with notches o', by which it engages a pin, o'', or other suitable catch projecting from the sides of the leaf, which slides on the guide-post n.

The dumping of the mold-board is effected 90 by first lifting the mold-board by raising the lever or crank i'' of the rod i, and then raising the rear end of the latch o, so as to liberate it from the pin o'', and then pushing the latch forward, as represented in Fig. 6 of the drawings. The mold-board is restored to its operative or normal position by drawing back 95 the latch o and retaining it by entering the pin o'' into the notch o', and then lowering the mold-board by lowering the free end of the lever i''.

In order to transmit the draft directly to the mold-board-supporting-arms B B, I employ a draft-link, I, arranged movable longitudinally across the forward axle, A, and independently 105 thereof, preferably extended through apertures in the head-block A''. With the rear end of the said draft-link I connect a pulley-block, N, by means of a yoke, L, which rises from opposite ends of the link and is extended 110 across the top of the head-block A'', the pulley-block N being hung on the rear upright portion of the yoke and adapted to slide vertically thereon, for the purpose hereinafter explained. Around the pulley of the pulley-block N passes a draft-chain, r, which by either 115 rods or extension of the chain is connected to the rear ends of the arms B B. From a point back of the rear end of the draft-link I rises, toward opposite sides of the carriage and forward over the axle A and across in front of the head-block A'', guides t t, upon which the pulley-block N slides when the forward axle 120 is cramped or turned on the king-bolt. Said pulley-block and adjacent portion of the draft-chain are thereby raised clear from the wheels 125 W.

To relieve the horses from jars and the draft-connection from excessive strain I interpose 130 between the whiffletree and draft-connections a spring-coupling, u, of the form of a sleeve, having its forward end adapted for the attachment of the whiffletree and its rear end provided with a rigid cap, which is perforated and

has extending through it a rod, the outer end of which is connected to the draft-link I, and the inner end has connected to it a nut, and between this nut and the cap on the rear end 5 of the sleeve is a spiral spring surrounding the rod.

Having described my invention, what I claim is—

1. In a road-scraper, the combination, with 10 the carriage-frame, of parallel horizontally-swinging beams pivoted to said frame, clamps for adjustably retaining said beams in their positions, arms extending from one toward the other of said beams, hangers connected to the 15 latter beam and supporting the free ends of the arms, and the mold-board connected to said arms, as set forth and shown.

2. In a road-scraper, the combination, with 20 the carriage-frame, of parallel horizontally-swinging beams pivoted, respectively, to the forward and rear portions of said frame at the center of the line of draft, clamps for adjustably retaining said beams in their positions, rearwardly-extended arms hinged to the 25 aforesaid forward beam, vertically-adjustable hangers on the rear beam supporting the free ends of the aforesaid arms, and the mold-board connected to said arms, as set forth.

3. In a road-scraper, the combination, with 30 the carriage-frame, of parallel horizontally-swinging beams pivoted, respectively, to the forward and rear portions of said frame at the center of the line of draft, clamps for adjustably retaining said beams in their positions, 35 rearwardly-extended arms hinged on the aforesaid forward beam, cranked shafts on the rear beam, hangers connecting the free ends of the aforesaid arms with the cranked shafts, levers on said shafts, pawls on the levers, toothed 40 sectors on the rear beam adapted to be engaged by the pawls, and the mold-board connected to the free ends of the aforesaid arms, substantially as described and shown.

4. In a road-scraper, the combination, with 45 the carriage-frame and the mold-board-carrying beams pivoted on said frame to swing horizontally into different angles to the line of draft, of bars adjustably connected to opposite sides of the carriage-frame and extending 50 across one of the aforesaid beams, and provided with locking-notches for engaging said beam and clamps for confining the bars in their locking position, substantially as set forth.

5. In a road-scraper, the combination, with 55 the carriage-frame and the mold-board-carrying beams pivoted on said frame to swing horizontally into different angles to the line of draft, of bars pivoted at one end on opposite sides of the carriage-frame and extending 60 across one of the aforesaid beams, and provided with locking-notches engaging said beam, levers pivoted on the frame and connected with the free ends of the aforesaid locking-bars, and ratchets on the frame adapted to hold the free 65 ends of the levers, substantially as described and shown.

6. In combination with the horizontal swing-

ing beams C C', vertically-adjustable arms B, and mold-board M, the bracket a, secured to said arm, and the hinge b, arranged with its 70 joint horizontally and at the lower end of the bracket, and having one of its leaves swiveled longitudinally and axially at right angles to the joint of the hinge and inclined rearwardly at its upper end, and the other leaf pivoted 75 on the mold-board axially at right angles to the planes of said latter parts, substantially as described and shown.

7. In combination with the carriage-frame, the beams C C', pivoted on said frame in the 80 center of the line of draft, the longitudinal coupling-bars D D, pivoted to the ends of said beams, the arms B B, supported by the beams C C', and the mold-board M, connected to said arms by universal-joints, substantially as and 85 for the purpose specified.

8. In combination with the carriage, mold-board, and arms carrying said mold-board, a draft-link arranged movably longitudinally across the forward axle and independently 90 thereof, and draft-connections between said link and the aforesaid arms, as set forth and shown.

9. In combination with the carriage, horizontally-swinging beams, arms connected with 95 said beams, and mold-board carried by said arms, a draft-link arranged movably longitudinally across the forward axle and independently thereof, a pulley connected to said link, and a draft chain passing around the 100 pulley and connected to the mold-board-carrying arms at opposite sides of the carriage, substantially as and for the purpose specified.

10. In combination with the carriage, horizontally-swinging beams, arms connected with 105 said beams, and the mold-board carried by said arms, a draft-link arranged movably longitudinally across the forward axle and independently thereof, a yoke rising from said link, a pulley hung movably vertically on said 110 yoke, a draft-chain passing around said pulley and connected to the mold-board-carrying arms at opposite sides of the carriage, and guides extending from the rear of the draft-link forward and rising over the forward 115 axle to carry the pulley clear of the wheels when turning said axle, as set forth.

11. In combination with the carriage, swing- 120 ing beams, arms connected with said beams, and mold-board carried by said arms, a draft-link arranged movably across the forward axle and independently thereof, a yoke rising from opposite ends of said draft-link and extending across the top of the head-block, a pulley hung movably vertically on the yoke back of 125 the head-block, draft-chains passing around the pulley and connected to the mold-board-carrying arms, guides extending from the rear of the draft-link forward and rising over the axle and above the wheels, and a spring-coupling 130 on the forward end of the aforesaid coupling-link and adapted for the attachment of the whiffletree, all combined substantially as described and shown.

12. In combination with the carriage and vertically-movable and forward-tilting mold-board, a guide-post on the carriage, a hinge arranged with its joint near the bottom edge ⁵ of the mold-board and having one leaf connected to the mold-board and the other leaf sliding vertically on the aforesaid guide-post, and a latch for holding the mold-board in its operative position, as set forth.
13. In combination with the carriage and the vertically-movable and forward-tilting mold-board adapted to be set at different angles to the line of draft, a guide-post on the carriage, a hinge arranged with its joint near ¹⁵ the bottom of the mold-board and having one

leaf pivoted on the mold-board and the other leaf sliding vertically on the guide-post, a latch connected to the upper end of the leaf, which is pivoted on the mold-board, and a catch on the guide-post adapted to engage the ²⁰ latch, substantially as described and shown.

In testimony whereof I have hereunto signed my name and affixed my seal, in the presence of two attesting witnesses, at Syracuse, in the county of Onondaga, in the State of New York, ²⁵ this 9th day of October, 1886.
